UNITED STATES PATENT OFFICE.

LOUIS BUTLER, OF HOUSTON, TEXAS.

OIL-BURNER.

1,085,195.

Specification of Letters Patent. Patented Jan. 27, 1914.

Application filed September 22, 1913. Serial No. 791,250.

To all whom it may concern:

Be it known that I, LOUIS BUTLER, a citizen of the United States, residing at Houston, in the county of Harris and State of Texas, have invented certain new and useful Improvements in Oil-Burners, of which the following is a specification.

This invention relates to new and useful improvements in oil burners and is designed 10 to provide a device of the character described for utilizing kerosene and other similar fuel and for conveniently and effectively converting the same into gas under the heating action of the burner itself.

15 Another object is to provide for taking the gas from the generator and carrying the same to the burner proper, where combustion takes place, in a simple and efficient manner.

20 Another object of the invention resides in the provision of a fuel nozzle and a needle valve for controlling the passage of fuel thereto, said valve being so constructed that by its operation it cannot enlarge the nozzle orifice and thereby permit the flow of too much fuel therethrough.

With the above and other objects in view, the invention has particular relation to certain novel features, of construction, operation and arrangement of parts, an example 30 of which is given in this specification and illustrated in the accompanying drawings, wherein—

Figure 1 is a sectional side elevation of the burner, Fig. 2 is a sectional side elevation of the nozzle, showing the connecting parts, and Fig. 3 shows the burner in inverted position, showing also the fuel tank and the service pipe connected therewith.

40 Referring now more particularly to the drawings, wherein like numerals of reference designate similar parts in each of the figures, the numeral 1 refers to a horizontal cylindrical shell or casing which forms the generator of the burner and is provided at its inlet or rear end with a reducer 2 which is screwed thereover to partially close said end and is provided with a central internally threaded perforation 3.

45 The numeral 4 refers to a conical shaped nozzle, the enlarged end of which is externally threaded and screwed into the inner end of the perforation 3 and the inner end of which projects into the generator 1. This 55 nozzle has a longitudinal passageway 5 therein, which is conical in shape. A valve

nipple 6 is provided which is outwardly threaded at each end, and one end of which is screwed into the outer end of the perforation 3. Screwed on to the other end of this nipple is the valve casing 7 and extending through said casing and nipple, is the needle valve 8 whose inner end is abruptly reduced, forming the annular shoulder 9, said reduced end conforming in shape to the 60 passageway 5 and controlling the flow of fuel therethrough. The outer end of the needle valve 8 has the hand wheel 10 and an intermediate section thereof is threaded, through a correspondingly threaded portion 65 of the casing 7, so that by turning the hand wheel 10 the needle valve may be controlled. A suitable service pipe 11 is connected to the nozzle and is in communication with a source of supply—as, for example, an elevated tank 70 75 12 located at a distance from the burner, so as to preclude the possibility of the ignition of the oil in said tank. A suitable control valve 13 is carried by the service pipe so as to control the supply of liquid fuel to the 80 nozzle.

The forward end of the generator is provided with an elbow 14, one end of which is secured over the said end of said generator and the other end of which receives the bushing 15.

The numeral 16 refers to an L, one end of which is secured in the bushing 15 and in the other end of which one end of the burner pipe 17 is secured so as to bring said burner 90 pipe parallel with the generator 1. The other end of this burner pipe is closed by means of the cap 18 which is secured thereover. The burner pipe is provided with orifices 19, positioned in the side thereof 95 toward the generator 1, through which the gas is designed to escape in the form of a flame.

In the operation of the device, oil is admitted to the interior of the generator 1 100 through the nozzle 4, said oil collecting in the generator 1. Heat is then applied to the generator in any preferred manner, so as to convert the oil into gas, which will pass through the bushing 15 and the L 16 to the 105 burner 17 and through the perforations 19 thereof where it may be ignited by means of a match or otherwise so as to emit flames which strike the generator so as to maintain said generator in a heated condition to 110 continue the formation of gas.

Particular attention is called to the forma-

tion of the nozzle 4 and the needle valve 8 and it is pointed out that the inward movement of said valve is limited, by reason of the fact that the annular shoulder 9 of the valve is arranged to abut against the outer end of the nozzle 4, when the valve is completely closed. This construction prevents the point of the valve from gradually enlarging the passageway in the nozzle and thus permitting too much fuel to flow into the generator 1.

In case too much oil is admitted into the generator, it will not be completely gasified and soot will be formed in said generator, and in addition to the soot formation there will be the liability of an explosion. The specific construction of the nozzle and valve shown obviates these defects and provides for the complete and exact control of the flow of fuel through the nozzle and into the generator.

While no specific application of the present form of burner has been shown, the device is particularly designed for application for cook stoves, although it may be used to generate heat for any purpose whatsoever.

While I have shown only one form of the invention, it is apparent that the specific construction thereof may be varied to suit the different applications of the burner and I hereby reserve the right to make such variations in the construction thereof as will not depart from the principle of the invention, as embodied in the appended claims.

35. What I claim is:—

1. An oil burner including a generating chamber, a reducer secured over one end thereof, a fuel nozzle, conical in shape, the enlarged end of which is secured in said reducer and the other end of which projects within said chamber, said nozzle having a conical shaped passageway extending lengthwise therethrough, a tubular valve nipple, one end of which is secured in said reducer, said nipple being alined with the nozzle, a valve casing secured upon the other end of

said nipple, and a needle valve extending through said casing and nipple and having a threaded connection with the casing, the inner end of said valve being reduced and forming an abrupt shoulder with the stem of the valve, said reduced end being tapered and projecting into the passageway of the nozzle and said shoulder abutting against the outer end of the nozzle when said passageway is completely closed by said valve.

2. An oil burner including a generating chamber, a reducer secured over one end thereof, a fuel nozzle, conical in shape, the enlarged end of which is secured in said reducer and the other end of which projects within said chamber, said nozzle having a conical shaped passageway extending lengthwise therethrough, a tubular valve nipple, one end of which is secured in said reducer, said nipple being alined with the nozzle, a valve casing secured upon the other end of said nipple, a needle valve extending through said casing and nipple and having a threaded connection with the casing, the inner end of said valve being reduced and forming an abrupt shoulder with the stem of the valve, said reduced end being tapered and projecting into the passageway of the nozzle and said shoulder abutting against the outer end of the nozzle when said passageway is completely closed by said valve, a service pipe connected with said nozzle through said nipple, and a burner pipe in operative relation with the generating chamber and arranged parallel thereto, the side of the burner pipe facing the generating chamber being provided with a plurality of perforations alined therealong.

In testimony whereof I have signed my name to this specification in the presence of two subscribing witnesses.

LOUIS BUTLER.
